POWER BOILER

Robert J. Rockefeller, Stroudsburg, Pa., assignor
to The International Boiler Works Co., East
Stroudsburg, Pa., a corporation of Pennsylvania

Application June 25, 1938, Serial No. 215,787

2 Claims. (Cl. 122—294)

This invention relates to boilers useful to generate steam at high pressures for power purposes.

My invention has for its chief aim to attain in power boilers, without necessitating use of superheaters, increased efficiency as regards the output of dry steam per square foot of heating surface, and per pound of fuel consumed with maintenance of the flue gas temperature at a minimum degree consistent with good draft conditions.

The foregoing advantages I realize in a boiler of simple, compact and rigid construction wherein the walls of the combustion chamber are water jacketed throughout and in direct communication with each other throughout their heights and transverse widths, as well as in communication at their tops with a longitudinally arranged water drum which in part forms the top or roof of said chamber; wherein the hollows of opposite walls are connected by longitudinally extending tubes inclined somewhat to the horizontal with establishment of a ring circuit for the water; and wherein crosswise baffles in the combustion chamber determine a sinuous up and down course of travel for the hot combustion gases along the length of the boiler so that they are caused to cross and recross the water tubes several times before escaping into the flue.

Other objects and attendant advantages will appear from the following description of the attached drawings wherein Fig. I is a view showing, in top plan, a power boiler conveniently embodying the present improvements.

Fig. II shows the boiler partly in side elevation and partly in longitudinal section.

Fig. III shows the front end elevation of the boiler.

Figs. IV and V are transverse sectional views taken as indicated respectively by the arrows IV—IV, V—V in Fig. II.

As herein illustrated, my improved boiler has a firebox 1 with water-jacketed end walls and longitudinal side walls 2, 3 and 4, 5 respectively, and a centrally-arranged lengthwise extending water drum 6 which is abutted by the inwardly directed upper end portions 4a, 5a of said side walls. At the corners of the boiler, the hollows of the end and side walls 2, 3 and 4, 5 communicate with each other throughout their heights and transverse widths as best shown in Figs. II, IV and V; and the drum 6 is cut away at opposite ends, as instanced in 7 in Fig. II, so as to communicate directly with the hollows of the end walls. Communication between the drum

6 and the tops of the side walls 4 and 5 is by way of serially arranged connecting nipples 8, see Figs. II, IV and V. Within the firebox the jacket hollows of the end walls 2 and 3 are connected by a multiplicity of longitudinally extending water tubes 9, which, as shown in Fig. II incline downwardly from the front toward the rear end of the boiler, with consequent establishment of the ring circuit for the water which is normally maintained at a level L in the drum 6. The direction of circulation of the water is as indicated by the dotted arrows in Fig. II, that is to say, upward in the hollow of the front wall 2, horizontally rearward in the drum 6, downward in the hollow of the rear wall 3, and forwardly in the tubes 9. A transverse partition 10 whereof the lower portion is constructed of masonry and the upper portion by a superimposed baffle 11 which latter is penetrated by the tubes 9, serves to set apart a combustion chamber 12 at the front end 10 of the boiler, said baffle terminating short of the top of said chamber. In the front end wall 2, below the level of the tubes 9, is a fire door opening 13, and in the rear end wall 3, above the level of the tubes 9, an opening 14 which leads 20 to a flue or chimney 15. Extending downwardly from the top of the rear subdivision of the firebox 1 is a transverse baffle 16 which terminates short of the bottom of said firebox. Due to the described arrangement of the baffles 11 and 16, a 30 sinuous up and down course is prescribed for the hot combustion gases in a direction longitudinally of the boiler, so that said gases are obliged to cross and recross the tubes 9 several times before escaping into the flue 15 for assurance of 35 a maximum thermal interchange between them and the water in said tubes. Feed water is introduced into the boiler through a longitudinal pipe 17 which enters the drum 6 at the front end, see Fig. II; and steam is taken from the 40 top of said drum through a centrally connecting pipe shown at 18. In the top of the drum 6 are tapped holes 19 and 20, 21 respectively for a water column, and for safety valves (not illustrated). There is also a tapped hole shown at 45 22 so that a steam injector may be installed if desired. Openings with removable panels 24, 25 in the side walls 3 and 4 of the boiler permit access for cleaning of the outsides of the tubes 9, which latter tubes are also accessible for internal cleaning or for replacement when necessary, upon removal of the plugs at 26, 27 from aligned tapped openings in the end walls 2 and 3. 50

The front and rear end walls 2 and 3 of the boiler are formed by spaced outer and inner 55

head sheets 28, 29 and 30, 31. The outer head sheets 28 and 30 have inwardly-extending flanges 28a, 30a respectively at their side edges, and semi-circular flanges 28b, 30b centrally of their top edges, said semi-circular flanges constituting the bottom halves of the end portions of the drum 6 at the regions of the cut-outs 7. As shown in Fig. II, the flanges 28b, 30b marginally overlap the cylindrical shell 32 of the drum 6 at the edges of the cut-outs 7 and are secured by rivets 33, 34. The inset heads 35, 36 of the drum 6 is in turn secured to said flanges and also to the ends of said shell by annularly-arranged rivets 37, 38 respectively. The inner head sheets 29, 31 of the end walls 2, 3 are depressed centrally of their top edges to form cradles for the drum 6, and have inwardly-directed flanges 29a, 31a which are continuous with their side and top edges. Edge margins of the head sheets 28, 30 of the wall 2 at the fire door opening 13 are flanged inwardly into abutting relation and welded together fluid-tight along the region of abutment as conventionally indicated at 39 in Fig. II. At their bottoms, the end walls 2 and 3 are closed by filler bars 40, 41 respectively (Fig. II) to which they may be either riveted or welded as found most convenient or expedient in practice.

The side walls 4 and 5 are similarly formed by suitably shaped spaced sheets 42, 43 and 44, 45, and the side edges of the outer sheets 42, 44 being overlapped upon the inwardly-directed flanges 28a, 30a of the outer head sheets 28, 30 of the end walls 2, 3 as best shown in Fig. I. The side edges of the inner sheets 43, 45 of the side walls 4 and 5 likewise overlap the inwardly-directed flanges 29a, 31a of the inner head sheets 29, 31 of the end walls 2, 3; and moreover have marginal retroversions 46, 47 at their tops at the regions of abutment of said side walls with the drum 6. As shown in Fig. IV, the outwardly-directed terminal flanges of the retroversions 46, 47 are overlapped by the top edges of the outer side wall sheets 42, 44, and the side walls 4, 5 are closed at the bottom by filler bars 48, 49 in a manner identical with that described of the end walls 2, 3. At overlap regions and junctures between the several wall sheets and the drum 6 where riveting is impractical, welding may be resorted to for the formation of fluid-tight joints. Strength and rigidity of the hollow walls is had through employment of suitably allocated stay bolts 50 more or less after common practice in the art. The flue opening 14 is the rear end wall 3 and the

panel-closed openings in the side walls 4, 5 respectively are preferably formed and finished like the fire door opening 13 in the front end wall 2 as shown.

In addition to the various appliances already mentioned, the boiler is provided, within the combustion chamber 12, with a fusible plug 51, see Fig. II, for safety purposes.

From the foregoing it will be evident that my invention affords a compact power boiler or high pressure steam generator whereof the component parts are few in number and interfitting and assembled in such a manner as to form a strong rigid unitary structure which is entirely self-contained, and in which the practical advantages hereinbefore pointed out are fully realized.

Having thus described my invention, I claim:

1. A sheet metal power boiler comprising a combustion chamber with jacketed end and side walls which are in full communication throughout their heights and transverse widths, and a horizontal cylindric steam drum which rests in central conformative recesses in the tops of the end walls and which has openings for communication respectively into the hollows of the end walls, equal in areas to the extents of mutual abutment, said end walls being formed by spaced pairs of head sheets whereof the inner ones have inwardly-directed flanges along their vertical edges and continuing inwardly-directed flanges across their tops for conformative abutment with the bottom of the steam drum, and whereof the outer ones have inwardly directed flanges along their vertical edges and outwardly-directed flanges at their tops for conformative abutment with the bottom of the steam drum, and said side walls being formed by spaced inner and outer sheets whereof the inner ones have outwardly-turned box flanges along their tops for abutment against opposite sides of the steam drum and for overlap by the top edges of the outer side wall sheets, said inner and outer side wall sheets having their vertical end edges respectively overlapping the corresponding inwardly directed vertical edge flanges on the inner and outer head sheets of the end walls.

2. A sheet metal power boiler according to claim 1, having horizontal tubes within the combustion chamber connecting the hollows of the end walls; and means within the combustion chamber defining a sinuous up and down course for the combustion gases longitudinally of the tubes.

ROBERT J. ROCKEFELLER.
